INVENTOR:

Svend A. Arntz

BY

Peter M. Boeseng
ATTORNEY

UNITED STATES PATENT OFFICE.

SVEND ARNE ARNTZ, OF MAMARONECK, NEW YORK, ASSIGNOR OF ONE-HALF TO HANS RUDOLF AUGUST STEFFENS, OF MAMARONECK, NEW YORK.

TOBACCO CAN.

Application filed June 19, 1926. Serial No. 117,034.

This invention relates to cans used as containers for different merchandise, packed in small quantities, such as tobacco, sticks of shaving soap, etc., and has for its object to produce an article that will facilitate the dispensation of the goods to which it is applied.

Another object of my invention is to produce a specimen of a can that besides the quality described above will, as a result of the special construction, present in part a surface that would be especially adaptable for the striking of matches thereon.

With the above and other objects in view, this invention consists of the novel features of construction, combination and arrangement of parts, hereinafter fully described, claimed, and illustrated in the accompanying drawings forming parts of this specification, and in which similar characters of reference indicate corresponding parts in all views, and in which:

Figure 1 is a sectional view of my invention, illustrating a longitudinal transverse sectional cut of a tobacco can with my device applied. Fig. 2 is a side view of same and Fig. 3 is a bottom view.

Referring more particularly to the drawings 10 indicates a tobacco can, having a lid 11 of the usual kind, and being supplied with a specially constructed bottom 12, said bottom has an upwardly projecting flange 13 and is adapted to perform a sliding movement inside of the box. To said bottom at 35 its lower central part is attached, as shown clearly in Fig. 3, an adjusting spring 14, said spring is connected to the bottom by means of two slits 15 formed in the latter, through which said spring is inserted. In 40 order to secure absolute steadiness of the spring, it may be soldered to the bottom, if desired.

The sides of the container are corrugated, as shown at 16, thereby forming inner stop-notches for engagement with said spring 14 during manipulation and adjustment of the latter to secure the bottom in desired position; the spring as will be seen at 17 is

shaped with a downward curvature. The outward corrugated sides of said box will 50 conveniently serve as a suitable surface upon which to strike matches and said surface may therefore, to increase the efficiency for said purpose, have applied to it, in section as shown at 18, a coat of sulphur 55 similar to match boxes.

As the can gradually is emptied of its contents, it will only be necessary to exert an upward pressure on the bottom to bring the contents of the can abreast with the upper 60 level, to be easily fetched.

It will be evident that the construction, as thus described, will constitute a valuable improvement of said containers and should not increase the manufacturing cost of same. 65

It is obvious that changes may be made in the form, construction and arrangement of the several parts, as shown, within the scope of the appended claim, without departing from the spirit of the invention, and I do 70 not therefore limit myself to the construction and arrangement shown and described herein.

What I claim as new, and desire to secure by Letters Patent of the United States, 75 is:

An article of manufacture, comprising a container, having a main body portion of substantially oblong shape; a lid fitted to the top of same; a movable bottom portion 80 with upwardly extending flanges and having a flat leaf spring connected to its lower surface by inserting the middle part of such spring through two slits formed in said bottom; corrugated sides adapted at their inner surfaces to form stop-seats for said spring, the latter being formed with a downward curvature; the outer corrugated surfaces of the sides of the container serving as a means for striking matches, a section of 85 said surface being sulphurized for the same purpose substantially as shown and described.

In testimony whereof I have hereunto affixed my signature.

SVEND ARNE ARNTZ.
